UNITED STATES PATENT OFFICE

CHARLES HUNT, OF WASHINGTON, DISTRICT OF COLUMBIA

LAUNCHING MACHINE

Application filed August 3, 1932. Serial No. 627,367.

The invention relates to launching mechanism and more particularly has reference to a mechanism for the launching of small boats such as life boats, whale boats, small power 5 craft, and the like, such as disclosed in my abandoned application Number 404,479.

Present practice in the launching of life boats from ships, employs fixed davits that are positioned along the sides of the ship, a 10 pair of davits being employed for each life boat. Between each pair of davits there is mounted upon blocks a life boat. The blocks rest upon the deck of the ship and are adjacent to the rail. When it is desired to 15 launch a life boat the boat falls of the davits, which are connected to the boat are actuated so as to raise the boat off of its blocks and the davits are swung outboard or over the side of the ship so as to cause the life boat to clear 20 the ship's sides. The life boat is then lowered by employing the boat falls secured at each end thereof.

In the present practice it is impossible to 25 launch a life boat from either side of the ship which is desired. A life boat mounted upon the starboard side must be launched on the starboard side as there are no means for positioning this boat so it may be launched from the port side of the vessel. It frequently 30 happens, at sea, that a life boat may only be launched from one side of the ship. In the manner of mounting now employed this is impossible and the life boats positioned upon one side of the vessel are useless.

As is well known it is practically impossible to launch a boat from a vessel on the windward side where there is an exceedingly heavy sea running. In the case of a ship 40 at times where it is necessary to abandon the vessel, it may be appreciated that in this event all of the life boats on the windward side would be useless and the life boat capacity would be halved.

Another serious condition which frequently 45 occurs is when the vessel has a decided list to one side. Upon such a condition occurring boats may be launched from only the listed side. As in the case previously mentioned this also halves the life boat capacity of the vessel with the result that if

it is necessary to abandon the ship the possibilities of saving all of the persons on board are greatly lowered.

While the above discussion has been limited to the launching of small boats from shipboard, it is apparent that similar disadvantages arise in the launching of boats from wharves, piers and the like. The boats are positioned on the sides and end of such structures, in a manner similar to that previously described and are launched from davits fixedly mounted upon the structure itself. It frequently happens that it is desirable to launch all of the boats from the same side of such a structure, yet the present practice does not permit this to be accomplished.

The major object of this invention is to devise a mechanism for launching a boat positioned at a considerable distance from the point where it is to be placed overboard.

An equally important object of this invention is the provision of means for launching life boats on either side of a ship.

Another object of the invention is to provide a novel movable davit and means for moving the same.

Another object of this invention is the provision of a device for launching a plurality of life boats from either side of a ship.

Still another object of the invention is the provision of a davit which may be used for shifting cargo and for other purposes on ship board.

Still another object of the invention is to provide a novel mounting for life boats which may be readily shifted upon tracks.

With these and other objects in view, which may be incident to my improvements, the invention consists in the parts and combinations to be hereinafter set forth and claimed, with the understanding that the several necessary elements comprising my invention may be varied in construction, proportions, and arrangement without departing from the spirit and scope of the appended claims.

The invention comprehends the construction of a boat launching mechanism which allows boats to be launched from either side of a ship. One manner of practically ef-

fecting the concept of this invention is the provision of movable supporting carriages for the life boats, these carriages adapted to be moved to either side of the ship and movable lifting, lowering and supporting means to be used for the purpose of launching the boats from the carriages.

In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

Fig. 1 is a side elevation of my boat launching mechanism mounted upon the boat deck of a ship.

Fig. 2 is a view similar to Fig. 1 but showing one of the life boats being launched.

Fig. 3 is a horizontal view of the boat launching mechanism.

Fig. 4 is a sectional view taken along the line 4—4 of Fig. 1 showing one of the davits associated with my device.

Fig. 5 is a sectional view taken along the line 5—5 of Fig. 4 and discloses a brake mechanism for controlling the actuation of the boat falls associated with the davit of Fig. 4.

Fig. 6 is a transverse sectional view of a boat carriage with the boat mounted thereon.

Fig. 7 is a sectional view showing the clutch mechanism associated with the winches employed with my device.

Fig. 8 shows the preferred embodiment of the davit construction of the invention and is an elevation of the mechanism.

Fig. 9 is an elevation showing a boat upon its boat carriage.

Fig. 10 is a modified form of boat carriage and is a front elevation thereof.

As shown in the drawings, the numeral 1 represents a boat deck of a vessel, while 2 represents a deck directly below the boat deck. The usual stanchions or supports 3 between the two decks are shown. Mounted at the center of the boat deck 1 so as to be as distant as possible from the damaging effect of waves are life boats 4. As it may be observed, sets of boat rails or trackways 5 extend entirely across the boat deck in a direction parallel to the transverse axis or the beam of the ship. The outer ends of the trackways 5 adjacent to the ship's sides, are sloped downwardly below the horizontal, the purpose of which will hereinafter appear.

Boat rails 5 are constructed either of I beams or of channel bars, the latter being preferred, and they are closed at their ends by a channel 6 which serves as a stop.

Adapted to be supported upon the boat rails 5 are a plurality of carriages 7, the preferred embodiment of which is shown in Figs. 9

and 10. As it may be here observed, each carriage is provided with a plurality of axles 8 having wheels 9 secured thereon. The wheels of each carriage are mounted in the channels 5 which form the trackways or guides and are freely rotatable therein so that the carriage may be readily moved. It should be noted that the upper portion of each carriage (Fig. 9) is of cradle-like shape so as to conform to the surface contour of the boat, while an opening or slot 10 is formed in the center of the upper surface of the carriage so that a boat keel may rest therein and the whole boat firmly supported on the carriage.

There is shown in Fig. 6 a slight modification of the carriage mounting or moving means. Here a carriage 7' (similar to the carriage 7) is provided with ball bearings 10 instead of wheels. In the use of such a carriage the channels 5' forming the boat rails are positioned so that their webs are parallel to the deck instead of perpendicular thereto, as in the construction previously described. It is apparent that by the use of the balls 10 the carriage 7' is freely movable on its rails.

Although I have shown the carriages mounted upon wheels and ball bearings, I wish it to be understood that other movable carrying means may be employed without departing from the spirit of the invention. For example, roller bearings may be employed if desired.

While I have shown two sets of boat rails and two carriages for each life boat, it is obvious that if it is desired, one large carriage, and one set of rails may be employed without departing from the spirit of the invention.

Positioned upon the outside of the boat rails 5, as seen in Fig. 3, are sets of davit rails 11. The davit rails 11 extend from each side of the ship to a point near the ship's center and are parallel to the boat rails 5. It should be noted that the outer ends of the davit rails 11 are also sloped below the horizontal as in the case of the boat rails and that they are formed of either I beams or channel bars, the latter being again preferred. The outer ends of each davit rail is closed by a channel 11' (Fig. 8) which provides a stop.

Adapted to be mounted upon the davit rails 11 are davit carriages 12 (the preferred embodiment of which is shown in Fig. 8), one for each set of rails. Each carriage is provided with axles 13 having wheels 14 secured thereon, and it is adapted to be mounted on the rails 11 in a manner similar to that described in connection with the boat carriages. Only two davit carriages are shown in the drawings, as may be observed from Fig. 3. However, upon the other side of the ship, since Fig. 3 is a broken view, two similar davit carriages are mounted upon the davit rails.

In the preferred embodiment of the invention there is mounted upon each davit carriage 12 a tubular davit 15 which is supported in a swivel socket 16. Also mounted upon the davit carriage is a suitable derrick which generally designated as 17. The derrick winch is provided with a cable 18 which after passing around the drum of the winch is secured to the boat falls 19. As it may be observed from the drawings, the boat falls may be connected to a life boat. It should be noted that two pairs of davits are provided, one pair for each side of the center of the ship.

15 The construction shown in Figs. 1, 2, 3, and 4 discloses a modification of the davit carriages. In these figures a substantial A frame construction having diagonal bracings 20 are employed to form the davits 15'. It should be noted that the upper end of the davit 15' is bent upon itself as shown at 21 and adapted to be suspended therefrom are the usual boat falls 25'. The lower end of the davit 15' is formed with a suitable piece which is bolted 25 or otherwise secured to a carriage 22 as may be observed from an inspection of Fig. 4. Carriage 22 is provided with suitable axles 23 having wheels 24 or other rotatable moving means secured thereon. The carriage 22 with 30 the davit 15' secured thereon is mounted in the davit tracks 11 in a manner similar to the mounting disclosed for the davit carriage in Fig. 8. It should be observed that the carriage 22 and the davit 15' have no derrick winch mounted thereon, there being provided a separate winch 17' for each davit. The winch 17' is suitably mounted upon the deck between the inner ends of each set of davit rails 11.

40 A boat fall cable or rope 25 is secured upon the drum of the winch 17' and extends through the falls 25'. Mounted upon each davit 15' is an arm 26 which carries a guide pulley 27 over which the cable 25 passes. 45 There is also provided upon the arm 27 a suitable safety brake 28 for the fall rope. The brake 28 is shown in Fig. 5 and it may be applied in conjunction with a brake or pawl upon the winch 17' or it may be used by itself 50 as desired.

In the preferred embodiment of the invention and in that shown in Figs. 1 through 5 it should be observed that upon the operation of the davit winches the boat falls may be raised or lowered as desired. Moreover, it is apparent that the davit carriages are freely movable in their trackways. While the davit carriages 22 and 12 are provided with moving means comprising wheels, it is to be 55 understood that other means, such for example as ball or roller bearings may be employed without departing from the spirit or scope of the invention.

Arranged between the inner ends of each set 60 of davit tracks are four deck winches 29 (Fig.

8). Each of the winches 29 is provided with a cable or chain 30 which is wound upon the drum of the winch. One end of the cable 30 is connected to the inner side, that is the side of the davit carriage nearest the ship's center, 70 as at 31, while the other end of the cable is connected to the outboard side of the carriage as shown at 32.

Each cable 30 passes over a suitable pulley or sheave 33 arranged below the davit track 75 and over a sheave 34 positioned adjacent the outer side of the boat deck. It may be observed that starting from the connection 31 each cable 30 passes around the drum of its deck winch, thence over the sheaves 33 and is 80 finally secured to the carriage at the connection point 32. It may be observed in Fig. 8 that upon rotation of the winch drum in a counter clockwise direction the cable 30 will be wound upon this drum in a similar direction. The effect of this becomes apparent in that it causes the davit carriage connected to this cable to move outwardly towards the side of the ship. Upon rotating the drum in an opposite direction, the davit carriage may 85 be moved inwardly.

Shown in Fig. 3 are deck winches 29' employed for moving the davit carriages 15' outwardly and inwardly with respect to the sides of the ship. For the sake of simplicity 90 in the drawings, only one end of the cable or chain 30', employed to move the davit carriages in an inboard and outboard direction, has been shown connected to each davit carriage 29'. It is obvious, however, that a construction similar to that shown in Fig. 8 permitting both ends of the davit carriage chain 30' to be connected to the carriage and allowing the chain to run over suitable guides or pulleys, can be readily employed with this 100 construction.

The davit winches 29' employed for moving the davit carriages, which are in line with each other and on opposite sides of the ship's center, are so arranged that the inner sides 110 of their drums 35 are adjacent to each other. These drums 35 are freely mounted upon a shaft 36 and between their inner ends is slidably keyed a male coupling member 37. The inner end of each winch drum 35 is adapted 115 to be engaged by the male coupling member 37 so that either drum may be rotated at will. Upon the ends of the shaft 36 are mounted suitable crank handles 38. By the suitable engagement of the coupling member 37 with either drum 35, upon rotation of a crank handle 38 in the proper direction, a davit carriage 15' on either side of the ship may be moved outboard or inboard as desired. In addition, suitable connections may be employed for connecting the deck winches 29' for opposite davit carriages, that is, davit carriages on the same side of the ship, together so that they may be actuated simultaneously and by the same operator. While 125 130

I have shown this construction as employed with the modification shown in Figs. 1 through 5, it will be well understood that it may be adapted to the preferred embodiment, shown in Fig. 8, for the actuation of the deck winches 29.

While the construction shown in Fig. 8 makes use of separate deck winches for each davit it is obvious that this can be done away with if it is desired, and each davit carriage be moved inwardly and outwardly by mechanism mounted thereon. To accomplish this, rack teeth may be formed upon the webs of the channel members and a suitable pinion capable of being rotated can be mounted upon the davit carriage. It is obvious that by the rotation of such a pinion, since it is in mesh with the rack teeth the carriage may be moved inwardly or outwardly as desired. Moreover, such a pinion may be rotated by the crank arm employed to actuate the winch mounted upon the davit carriage. This could be readily accomplished by a suitable clutch connection between the pinion and the winch crank shaft.

While it has been pointed out that the deck winches 29 employed with the construction shown in Fig. 8 may be eliminated, it is equally obvious that the deck winches 29' used with the davit having the A frame construction may be likewise done away with. This can also be readily accomplished by forming rack teeth upon the webs of the channel members which make up the davit rail and providing a rotatable pinion upon each davit carriage 15' adapted to mesh with the rack teeth. Such a pinion could be rotated from the davit carriage itself, and it is apparent that the carriage can be moved inwardly or outwardly as desired by the use of such construction. A construction similar to that employed for the actuation of the deck winches 29' is shown for the winches 17' which are used to operate the boat falls 25'.

It should be noted that the movable davit carriages with the davits mounted thereon may be used as derricks or winches for shifting cargo when it is desired. To accomplish this the davit tracks may be placed adjacent to, or directly over, the hatches. In the latter event the portion of the trackway directly over the hatches may be hinged either vertically or horizontally so as to move it out of the way for the removal of the cover of the hatch, or the hatch cover itself may be constructed of several removable pieces of material. It is obvious that the life boats, having been securely tied to the deck, the boat falls may be disconnected from them and the davits may be shifted upon the tracks for shifting and storing the cargo and ship gear.

From the foregoing description the method of operation of the device may be well understood. Assume, for example, that the life boats are to be launched upon the left

side of the ship as seen from the drawings. In this event the davits on the left of the ship center would be employed. The life boat is unleashed from its deck ties and the winches 29 are simultaneously operated so as to move the boat carriages, the davit carriages 12 and the life boat outboard or to the left. As the boat moves outwardly it leaves the boat carriage and is supported by the davits 15, and swings over the side of the ship. The winches 29 are actuated until the davits reach the outermost position where they are stopped by reason of the channel bar 11 forming the ends of each davit rail.

As the boat carriages are moved outwardly towards the side of the ship, it is apparent because of the downward slope given to the boat rails and because of the fact that the boat is supported by the davits, that the boat becomes free from its engagement with the boat carriages. After the boat has left its carriages the latter continue downwardly towards the end of the boat rails 5 and are stopped by the channel member 6 at the ends of the boat rails.

The davits having been moved to the extreme outward position the life boat can be lowered and the descent of the boat may be regulated by the use of the brake provided on the winch of the davit carriage. In the construction shown in Fig. 8 a suitable shaft may be connected between the two davit winches 14 so that they may be operated simultaneously and by one man.

If it is desired to launch another boat from the same side of the ship, the davits 15, shown in Fig. 8, are turned in their swivels 16 and the boat falls are secured to an unleashed boat. By actuating the boat falls, this boat will be pulled towards the davits and freed from engagement with its boat carriages. The davit may then be turned outwardly and the boat lowered over the sides of the ship.

In the event that a boat is to be lowered to the right of the ship's center, as shown in the drawings, the winches on the right are employed to similarly launch the boat on this side. Thus it may be seen that any number of boats mounted upon the boat track may be launched from either or from both sides of the vessel.

While the operation of the preferred embodiment of the invention has been described, it will be appreciated that the construction shown in Figs. 1 through 5 inclusive is similarly actuated. Here when it is desired to launch a boat upon the left side of the ship the deck winches 29' are actuated so as to cause the pair of davit carriages 15' on the left of the ship's center to be moved outwardly, thus moving the boat with them. After this operation the deck winches 17' are employed to operate the boat falls so as to lower the boat suspended therefrom. It may be appreciated that a conventional con-

nection may be employed between the davit winches 17' for the operation of the opposite falls connected to the same life boat so that these falls may be simultaneously actuated 5 by one man.

In this construction, when it is desired to lower another boat upon the same side of the ship, it is necessary to move the davit carriages 15' inboard and secure the boat falls 10 suspended therefrom to an unlaunched boat. After this operation the davits are moved outwardly and the boat launched in a similar manner to that just described. It will be appreciated that if a boat is to be lowered 15 to the right of the ship's center the winches operating the boat falls and those employed for moving the davit carriages on the right will be actuated.

While I have shown two sets of boat rails 20 5 for the boat carriages, it may be appreciated that by employing more than two sets of rails each boat carriage may be positioned adjacent to the outward ends of the boat rails. In the event that all the boats are to be 25 launched from one side of the ship, such a construction would prevent the boat carriages of two or more boats from backing up upon each other in the trackways. For example, consider that the life boats are 30 mounted in groups of three, then five sets of rails would be provided. One boat would be supported on a single carriage adapted to run on the center rail set, while another boat would be supported by two carriages 35 adapted to move upon the rail sets adjacent to and on opposite sides of the center track and the third boat would be supported on two carriages, one on each of the end rail sets. If the boats are to be mounted in 40 groups of more than three, it is obvious that more rail sets may be added to the foregoing construction.

It has been pointed out that the present 45 method of mounting life boats on ships positions them adjacent to the rail of the vessel. It frequently happens, during big storms, that these boats are either washed away or 50 smashed due to the impact of the waves. By providing mechanism for shifting or moving the life boats to either side of the ship, it is possible to locate them in such a position 55 on shipboard that they are less likely to suffer damage from large waves breaking over them.

While the foregoing mechanism has been 60 shown associated with a ship for the purpose of launching small boats therefrom, it is to be understood that the invention is not limited to this particular use. Obviously the mechanism may be employed on any structure from which boats are to be launched, such as piers, wharves and the like.

From the foregoing description it may be 65 appreciated that I have provided a boat

launching mechanism capable of launching a boat positioned at a considerable distance from the point where it is to be placed overboard. Moreover, it may be seen that by the use of my mechanism one or more boats 70 may be launched from any desired side of a ship. It is also apparent that I have provided a novel movable davit which in addition to being used for launching boats may be employed in connection with the storage 75 of articles in the hold of a vessel or for other purposes. Likewise it may be seen that I have devised a boat carriage which may be readily moved from side to side of the ship. Also it may be appreciated that I have devised 80 a mechanism which allows life boats to be so located on a ship that the damaging effects of waves to the boats are minimized.

While I have shown and described the preferred embodiment of my invention, I wish 85 it to be understood that I do not confine myself to the precise details of construction herein set forth, by way of illustration, as it is apparent that many changes and variations 90 may be made therein, by those skilled in the art, without departing from the spirit of the invention or exceeding the scope of the appended claims.

I claim:

1. A mechanism for launching a life boat 95 from either side of a ship comprising boat carriages for supporting the boat, pairs of davits for raising, holding, and lowering the boat, said davits being mounted upon separate davit carriages, trackways for said boat 100 carriages and said davit carriages, a rotatable drum for each davit carriage, a cable wound upon each drum the ends thereof being secured to a davit carriage, and means for actuating a pair of said drums so as to move a 105 pair of davits and the boat carriages to either side of the ship in order to position the boat for launching.

2. A mechanism for launching a boat, comprising boat carriages for supporting the boat, pairs of davits for raising, holding, and lowering the boat, said davits being mounted on separate davit carriages, trackways for said boat carriages and davit carriages, the 110 ends of said boat carriage trackways adjacent to the point of launching being sloped downwardly from the horizontal, a rotatable drum for each davit carriage, a cable wound upon each drum, the ends thereof being secured to a davit carriage, and means for actuating a pair of said drums so as to move a pair of 115 davits and the boat carriages to either side of the ship in order to position the boat for launching.

3. A mechanism for launching a life boat 120 from a ship comprising carriages for supporting a life boat, pairs of davits for raising, holding, and lowering said boat, trackways for said boat carriages, the boat carriage 125 trackways extending from one side of the ship 130

to the other, the ends thereof adjacent to the sides of the ship being sloped downwardly from the horizontal, and means for moving a pair of davits so as to position the boat carriage and the boat on either side of the ship for launching.

4. A mechanism for launching life boats from a ship comprising a plurality of boat carriages adapted to support a plurality of life boats, pairs of davits for raising, supporting, and lowering the boats, each of said davits being mounted upon a carriage, and means for separately moving each boat carriage and a pair of davits to either side of the ship so as to separately position each boat for launching, said means comprising a rotatable drum for each davit carriage, a cable wound upon each drum, the ends thereof being secured to a davit carriage, and means for actuating a pair of said drums so as to move a pair of said davits and a boat carriage.

5. A mechanism for launching life boats from a ship comprising arranging a plurality of life boats upon a plurality of movable carriages, said carriages being mounted upon trackways extending from one side of the ship to the other, pairs of davits for raising, holding, and lowering a boat, each of said davits being mounted upon a movable carriage, and means for moving a pair of davits to either side of the ship so as to separately position each boat for launching, said means comprising a rotatable drum for each carriage, a cable wound upon each drum, the ends thereof being secured to a davit carriage, and means for actuating a pair of said drums so as to move a pair of davits and a boat carriage.

6. A mechanism for launching a life boat from a ship, said mechanism comprising boat carriages adapted to have a boat mounted thereon, trackways for said boat carriages extending from one side of the ship to the other, pairs of movable davits adapted to raise, support and lower the boat, stationary means for moving said carriages upon the trackways to either side of the ship, and stationary means for moving a pair of davits in the same direction as the carriages so as to launch the life boat.

7. A mechanism for launching a life boat from either side of a ship comprising boat carriages for supporting the boat, pairs of davits for raising, holding, and lowering said boat, said davits being mounted upon separate davit carriages, trackways for said boat carriages, the boat carriage trackways extending from one side of the ship to the other, the ends thereof adjacent to the sides of the ship being sloped downwardly from the horizontal, trackways for said davit carriages, a rotatable drum for each davit carriage, a cable wound upon each drum, the ends of said cable being secured to a davit carriage, and means for actuating a pair of said drums so

as to move a pair of davits and the boat carriages to either side of the ship in order to position the boat for launching.

In testimony whereof I affix my signature.
